United States Patent

Des. 238,990
Patented Mar. 2, 1976

238,990

MOBILE CHAIR OR SIMILAR ARTICLE

Rafael A. Galvez, 1255 W. 53rd St., Apt. 106,
Hialeah, Fla. 33012

Filed May 6, 1974, Ser. No. 467,897

Term of patent 14 years

Int. Cl. D6—01

U.S. CL. D6—78

FIG. 1

FIG. 2

FIG. 4

FIG. 3

FIG. 1 is a perspective view of a mobile chair or similar article showing my new design;

FIG. 2 is a front elevational view of FIG. 1;

FIG. 3 is a side elevational view of FIG. 1, the opposite side being a mirror image of that shown;

FIG. 4 is a top plan view of FIG. 1; and

FIG. 5 is a rear elevational view of FIG. 1.

I claim:

The ornamental design for a mobile chair or similar article, as shown.
